UNITED STATES PATENT OFFICE.

ROLAND HICKS, OF REMER, MINNESOTA.

POLISHING CLOTH.

Application filed July 30, 1924. Serial No. 729,140.

This invention relates to toilet articles and the method of making same, and has special reference to a nail polishing cloth.

The principal object of the invention is to provide a convenient device for use in polishing the finger nails.

Another object is to so combine a polishing cloth and the ingredients for producing the polish as to make the most convenient toilet accessory possible.

Other objects and advantages of the novel combination will appear in the further description thereof.

The accompanying drawing, forming part of this application, is a perspective view of a person's hands during the employment of the cloth illustrating how the same may be used.

1 represents the cloth, which is preferably of porous weave, such as felt or the like, which is thoroughly impregnated with the polishing material, combining refined marl in powder form, mortar coloring also in powder form, and glycerine.

25 The process employed in impregnating the cloth is to first thoroughly saturate the dry cloth with the mixture of powdered marl and mortar coloring, then applying a liquid solution of the marl, mortar coloring, and glycerine to either side thereof, when the cloth being thus saturated and covered with the mixture is passed several times between rubber rollers under pressure so as to thoroughly force all of the material possible,

35 into the cloth simultaneously with the removal of any surplus which the cloth will not take up.

After this preparation, the cloth is ready for use and will retain its detergent or polishing properties almost indefinitely, or at 40 least so long as any of the properties of the glycerine remain with the cloth.

In this manner an exceedingly simple and convenient device for the purpose of 45 polishing is provided and one that occupies the least possible space avoiding the necessity of separate receptacles, buffers and polishers now commonly used.

Having thus described my invention, what I claim and desire to secure by Letters Patent, is:

1. The herein described method of making a finger nail polishing article consisting of impregnating a piece of porous cloth with a granular abrasive substance in dry 55 form, then applying a solution consisting of the same substance and glycerine, and then passing the cloth thus saturated intermediate of squeezing rollers for the purpose described.

2. The herein described method of making a finger nail polishing article consisting of impregnating a piece of porous cloth with a granular abrasive substance in dry form, applying a liquid solution thereto, and removing the surplus composition by pressure.

ROLAND HICKS.
